Inventor:
Alfred M. Ziegler,
Dag Emery, Booth, Jimmy, Nancy
Attig.

UNITED STATES PATENT OFFICE.

ALFRED MAY ZIEGLER, OF NEWTON, MASSACHUSETTS.

GARTER.

Application filed December 21, 1923. Serial No. 681,980.

To all whom it may concern:

Be it known that I, ALFRED M. ZIEGLER, a citizen of the United States, and a resident of Newton, county of Middlesex, and 5 State of Massachusetts, have invented an Improvement in Garters, of which the following description, in connection with the accompanying drawings, is a specification, like characters on the drawings representing 10 like parts.

This invention relates to garters and the object is to provide a garter of superior wearing qualities and of greatly increased comfort as compared with those at present 15 known.

My invention will be understood by reference to the following description of the illustrative embodiment thereof which I have shown by way of example in the accompanying 20 drawings, wherein:

Fig. 1 is an elevation of the garter; and Figs. 2 and 3 are sections on the lines 2—2 and 3—3 of Fig. 1 respectively and illustrates the garter in use.

Referring to the drawings, I have shown 25 in Fig. 1 a garter illustrative of my invention and which may be as there shown of the kind more fully described in my application for patent Serial No. 542,011, filed March 8, 1922, and embodying a so-called pad 5 of a general lozenge form from which depends the clasp 7 to be secured to the sock and from one side of which projects the leg encircling band 30

9 which, as is customary, is looped back through the body of a clasp member 11 provided with the eye 13 and is secured to itself by means of the adjusting buckle 15. In the example of the invention shown,

40 as more fully described in my prior application referred to, the eye 13 of the clasp 11 takes over a stud or post 17 which is connected to the side of the pad 5 by a short piece 19 of inextensible material, the whole 45 being covered by a loop 21 of material similar to the band 9 which projects from the side of the pad and through the overlying portion of which the neck of the stud 17 projects. This has the advantage of re-

50 moving the clasp 11 from the face of the pad 5 which is usually covered with relatively fine fabric which would be easily worn by the abrasion of the clasp and the loop 21 also has relatively soft flexible corners

55 which are not likely to gouge into the leg.

One of the defects of a garter construc-

tion of this type and which is perhaps inherent in any garment having a constricting band encircling a portion of the body is that it exerts pressure against the leg 60 and may cut into the same or become irksome after continued wear. This defect has been considerably emphasized by the common adoption among men of knee-length underdrawers so that the garter encircles 65 the bare leg. One result has been the general development of the so-called "wide web" garter in which the band 9 is of relatively great width as in the garter herein illustrated but this has not entirely done away 70 with the defect referred to.

One principal object of my invention is to do away with or minimize the disadvantages and in the form of the invention which I have chosen for purposes of illustration I utilize the buckle 15 and clasp 11 to obtain the desired results to a practical and beneficial extent particularly as to that portion of the leg encircling band 9 which is double and which thus is stiffer 75 and has more unyielding edges and is more likely to cut into the flesh. At the same time I obtain certain other advantages as will appear as the description proceeds and obviate the disadvantages which have arisen 80 in the ordinary type of garter from the use of such metal fittings which, being stiff and projecting beyond the edges of the leg band proper, have tended to press into and mark 85 the leg.

In accordance with my invention I may provide at suitable intervals throughout the leg band stiffening means which will hold it transversely cupped with the convexity toward the leg and with the edges of the band 95 which tend to dig into the flesh held away from the leg. In the embodiment of the invention illustrated I utilize for these stiffening means the clasp 11 and the buckle 15 which, lying at opposite ends of the doubled portion of the web which is naturally the stiffest and most unyielding, will have the desired effect upon this portion of the garter and obtain the desired results to a practical extent. As shown more particularly in Figs. 100 2 and 3, I give to the transversely extending metallic fittings 11 and 15 a curvature throughout their length so that when the garter is clasped around the leg the convexity of this curve is presented to the leg. 105 The pressure of the garter against the leg is thus graduated from a maximum at the

middle of the band to nothing at the edges with a great increase in comfort. The ends of the relatively stiff buckles are turned away from the leg and in ordinary use will even be somewhat spaced therefrom as shown in Fig. 3. At the same time these fittings, as best shown in Fig. 3, hold the portion of the band between them, in this instance the double portion which is relatively stiff, in convex form with the convexity toward the leg, as shown in Fig. 3, and hold the edges of the band which are likely to cut into the flesh directed away from the leg so that the pressure of this portion of the band upon the leg is the pressure of an extended rounded surface instead of the pressing in of a flat surface with palpable edges. The edges of the band being slightly spaced from the leg permit ventilation and the garter is cooler and less irksome to the wearer.

Further advantages arise from the curved construction of the clasp 11 as best shown in Fig. 2. It will be noted that the eye portion 13 is presented in a plane offset from the rest of the clasp and catching it around the post 17 is thus facilitated as the remainder of the clasp 11 is not in the way but on the contrary the arrangement is such that the eye 13 can be projected forward and reached out to engage the post 17 with substantially as much facility as if it were not attached to a relatively long transverse member. Furthermore, this action can take place from any desired angle and it will be noted from Fig. 2 that the bearing of the clasp 11 is a relatively restricted one and the ends of the clasp are away from the leg and this facilitates swivelling movement of the clasp around the post 17 permitting the garter to adapt itself to different sizes and shapes of leg and to the particular angle at which the band has been brought around the leg and to any movement of the leg while the garter is being worn.

This spacing of the ends of the clasp 13 away from the leg also brings them away from the portion 21 of the garter or similar part carrying the post 17. This prevents their rubbing on the face of this part and consequently the garter wears out less quickly than it otherwise would. The construction furthermore prevents an end of the clasp 13 in its swivelling movement from buckling up or folding one of the free corners of the member 21 causing a projection which would press into the flesh and cause discomfort.

I have described in detail the particular

embodiment of my invention shown by way of example in the accompanying drawing and in this type I have utilized suitable forms of the customary metallic fittings for attaining certain objects of the invention and at the same time attaining certain other advantages which will be understood from a perusal of the preceding description. It will be obvious, however, that within the scope of my invention the different constructions attaining certain only of the various advantages enumerated and other means than the fittings illustrated may be utilized for effecting the desired results. With these considerations in mind I shall in the following claims express what I consider to be new and desire to secure by Letters Patent.

Claims.

1. A garter comprising a leg encircling band having an adjusting buckle and a clasp each curved throughout its length to provide a convex inner surface which is toward the leg when the garter is in use.

2. A garter comprising a leg encircling band having a post and eye connection including a clasp member comprising a body through which the end of the band is threaded and having a substantially central eye to engage the post, said body being curved throughout its length to provide a convex inner surface which is toward the leg when the garter is in use, whereby the eye portion is presented inwardly of the marginal portions and its engagement with the post facilitated and the marginal portions are held spaced from the post supporting portion of the garter to minimize wear on the latter and to facilitate swivelling movement of the connection.

3. A garter comprising a leg encircling band having its end doubled back and secured by an adjusting buckle curved throughout its length to provide a convex inner surface which is toward the leg when the garter is in use, said buckle holding the margins of the relatively stiff doubled band away from the leg.

4. A garter comprising a leg encircling band of flexible webbing having associated therewith a plurality of transversely extending stiffening members each curved throughout its length and having a convex inner surface, said members being thus adapted to hold at least a portion of the band with the edges thereof directed away from the leg.

In testimony whereof, I have signed my name to this specification.

ALFRED MAY ZIEGLER.
